UNITED STATES PATENT OFFICE.

WILLARD L. RAY, OF NORTH ADAMS, MASSACHUSETTS.

IMPROVEMENT IN STEAM-TRAPS.

Specification forming part of Letters Patent No. 39,172, dated July 7, 1863.

To all whom it may concern:

Be it known that I, W. L. RAY, of North Adams, in the county of Berkshire and State of Massachusetts, have invented a new and useful Improvement in Steam-Traps; and I do hereby declare that the following is a full, clear, and exact description of the same, reference being had to the accompanying drawing, forming part of this specification, said drawing representing a central vertical section of a steam-trap constructed according to my invention.

This invention consists in a novel mode of combining a valve, a weight, expanding-pipe, and a stop in a steam-trap, whereby it is rendered very simple and durable and of very certain operation.

To enable others skilled in the art to construct and apply my invention, I will proceed to describe it with reference to the drawing.

A is a box or chamber of spherical or other form, screwed tightly onto the waste-pipe B in such manner that the end or mouth of the said pipe is situated within the said chamber or box near the center thereof. This pipe B is firmly secured at a suitable distance from the box A—say, about twelve feet—by a suitable fixed clamp or fastening, C, to any suitable fixed support, that the longitudinal expansion and contraction of the said pipe may produce a corresponding movement of the box or chamber, which is supported in such manner upon a suitable board or base, D, as to permit of the said movement. Opposite to the pipe B there is inserted into a suitable hollow socket, a, provided on the box or chamber A, a metal plug or plunger, E, which enters the said box or chamber in line with the said pipe, and protrudes some distance from the exterior thereof, the said plug or plunger being fitted to work easily in the said socket without a stuffing-box or other packing. The inner end of this plug or plunger constitutes a valve to which the end of the pipe B constitutes a seat, and for this purpose the said end of the plug or plunger may have a cavity formed in it for the reception of some soft composition or alloy, or of a piece of vulcanized india-rubber, to form the valve-face. From the bottom of the box or chamber A there descends a pipe, F, for carrying off the water of condensation which runs into the said box or chamber from the pipe.

G G' is an elbow lever arranged to work upon a fulcrum pin, b, secured in a fixed standard, H. One arm, G, of this lever projects downward from the fulcrum, and occupies a nearly-vertical position opposite to the outer end of the plug E, and the other arm, G', is either made very heavy to constitute a weight, as represented, or else has suspended from it a separate weight, which acts to press the arm G against the plug E, the said weight being sufficient to overcome the pressure of the steam upon the valve when the latter is in contact with and closes the end of the pipe B. Through the lower part of the arm G there is screwed a set-screw, I, the point of which is situated behind a fixed stop, J.

The operation of the trap is as follows: When the pipe B contains water, the length of the said pipe is such that there is an opening between its extremity and the valve at the inner end of the plug E, the outer end of which rests against the arm G of the lever, which is held stationary by the weight G' with the set-screw I, in contact with the stop J; but when the water has been expelled from the pipe B by steam, the said pipe expands sufficiently to bring its end in contact with the valve at the inner end of the plug E, and the continued expansion of the said pipe merely pushes the plug E outward and pushes back the arm G of the lever, the weight of which keeps the valve closed without the end of the pipe cutting the face of the valve or any part of the apparatus being strained. It is in this freedom from cutting the face of the valve or straining any part of the apparatus that the advantage of my trap principally consists. When the pipe B is again filled with water by condensation, the pipe becomes cooler and contracts, and its inner end is drawn away from the valve and opened to permit the water to run into the box A and out by the pipe F, the lever and plunger being arrested by the set-screw I coming in contact with the stop J. The set-screw I is applied to regulate the opening between the pipe B and the valve, the opening being increased by screwing forward the set-screw toward the stop and diminished by screwing back the said screw. The effect of the weight G' is increased or diminished by adjusting the fulcrum-pin b lower down or higher up in a slot, c, provided for the purpose in the standard H, or by increasing or

adjusting the weight on the horizontal arm of the lever when a movable weight is used.

It has been before mentioned that the plug E is fitted to the socket *a* without packing. The packing is not necessary, for the reason that when the valve is closed no steam enters the box A, and when the valve is open the water has free egress at F. The box A might be stationary, and the pipe B fitted to work in the said box, as the operation of the valve and pipe will then be the same as if the box were attached to the pipe. I prefer, however, to screw the pipe tightly into the box and allow the latter to move with the expansion and contraction of the pipe.

I do not confine myself to any particular arrangement of the weight and stop, in combination with the plug or valve; but

What I claim as my invention, and desire to secure by Letters Patent, is—

The plunger or valve E, weight G', and stop J, combined with each other and with the expanding-pipe B and box A, or its equivalent, to operate substantially as and for the purpose herein specified.

W. L. RAY.
